UNITED STATES PATENT OFFICE.

JULIUS ADLER, OF JERSEY CITY, NEW JERSEY.

DESIGN FOR A HAT OR CAP.

SPECIFICATION forming part of Design No. 21,178, dated November 17, 1891.

Application filed October 26, 1891. Serial No. 409,913. Term of patent 7 years.

To all whom it may concern:

Be it known that I, JULIUS ADLER, a citizen of the United States, residing at Jersey City, in the county of Hudson and State of New Jersey, have invented a new and original Design for Hats and Caps, of which the following is a full, clear, and exact description.

Reference is to be had to the accompanying drawings, forming a part of this specification, in which similar letters of reference indicate corresponding parts in both the views.

Figure 1 is a perspective view of the design, part being broken out; and Fig. 2 is a transverse section of the same.

The leading feature of the design consists of a plaited top A, with a button B located in

the center, and plaited inclined sides C, terminating at the lower edge in a plain band D. The top and side plaits are formed into a double or V-shaped beveled plate E at their junction, and a like beveled plait F is formed at the junction of the lowermost edge of the side C with the band D. The side C is inclined upwardly and outwardly, while the top A extends horizontally, or nearly so.

I claim—

The design herein shown and described.

JULIUS ADLER.
